COMBINED BODY REST AND FOOT SUPPORT UNIT

Fred A. Schmitt, Nutley, N.J., assignor to Litton Business Systems, Inc., New York, N.Y.

Filed Sept. 2, 1970, Ser. No. 24,815

Term of patent 14 years

Int. Cl. D6—02
U.S. Cl. D6—64

FIG. 1

FIG. 2

FIG. 3

FIG. 4

FIG. 1 is an isometric view of a combined body rest and foot support unit embodying my new design;

FIG. 2 is a front view of the support of FIG. 1;

FIG. 3 is a side view of the support of FIG. 1; and
FIG. 4 is a top view of the support of FIG. 1.

I claim:

The ornamental design for a combined body rest and foot support unit, as shown.
